UNITED STATES PATENT OFFICE

HARRY HERTZBERG, OF BROOKLYN, NEW YORK, ASSIGNOR, BY MESNE ASSIGNMENTS, TO THE M. PROPP CO. INC., OF NEW YORK, N. Y., A CORPORATION OF NEW YORK

ARMOR FOR ELECTRICAL CONNECTING PLUGS

Application filed January 8, 1927. Serial No. 159,822.

This invention relates to electrical circuit connecting devices and is particularly directed to attachment plugs.

Among the objects of this invention is to provide an electrical plug connector having a body of insulating material, and a metallic armor of improved construction to protect the same, the armor comprising few and simple parts, which shall be cheap to manufacture, easily fitted to form a rugged protection for the connector, and practical and efficient in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational view showing a plug connector fitted with an armor embodying the invention.

Fig. 2 is a side view of the armored plug, partly broken away to show the interior construction.

Fig. 3 is a front elevational view of one of the pair of identical improved armor plates.

Fig. 4 is a sectional view taken on line 4-4 of Fig. 3.

Fig. 5 is a top plan view of the armor section shown in Fig. 3.

Referring now more specifically to the drawings, the invention is shown applied to a connector plug 10 of any standard construction. As here shown, said plug 10 comprises a body portion of insulating material formed of two complementary parts or blocks 14a and 14b which may be held together by one or more clamping screws 17. Between said parts, there is secured to extend from one end a resilient supporting member 11 for leads 12. The specific shape of the connector plug can be varied according to the purpose for which the connector is to be used and the

resilient member 11 may comprise a helical coil through which said leads extend. Suitable anchorage is provided for positively securing the coil spring to the plug body in a simple and conventional manner.

The parts 14a and 14b of the plug enclose current carrying contact members as shown at 13 which connect with the leads 12 and are adapted to detachably connect with terminals of electric appliances (not shown).

Preferably, the parts 14a and 14b of the plug 10 cooperate to form an inclosure 15 for the contacts 13, said parts being pressed or moulded into suitable form so as to meet or engage one another along a plane or other surface of contact 16.

An improved armor or guard is provided for the insulating body portion to provide a better wearing surface and to prevent injury to the plug. The armor is formed of sheet metal and substantially incloses the complementary plug parts, exposing only the upper portions of the plug to be grasped by the operator so as to avoid contact with the armor in the event the same should become heated. The armor is secured to the insulating blocks by means of the fasteners or screws 17 passing transversely through the body portion which holds the plug parts assembled. Said screws, as here shown are arranged in spaced relation to each other and along a central longitudinal plane of the body.

For simplicity in assembling and manufacture, the armor is formed of two identical sections 18a and 18b, the longitudinal edges 18 of which meet along the plane of contact 16 of the insulation blocks.

The armor is arranged to have resilient engagement with the screws 17 whereby the screws are caused to clamp the parts 14a and 14b of the body portion together to evenly conform to the latter regardless of certain variations which always arise in the manufacture of connector plugs of the split type. For this purpose, ears or lugs 19 are formed in the armor, these being preferably stamped out from said sections in the form of offset tongue projections to provide resiliency. Said lugs extend inwardly of the armor sections into recesses 20 provided in the blocks 14a and 14b.

14b adapted to house the heads 17a of the screws 17, and also the nuts 21 engaging the thread ends of said screws. The lugs are engaged by said screw heads 17 and nuts 21, thus 5 constituting an anchorage to prevent movement of the armor sections with respect to the blocks. The lugs or ears may be made to conform to the shape of said recesses and nuts 21 which as here shown are hexagonal. Each 10 lug extends only partially around beneath a screw head or nut so as to permit swinging the lugs into proper alignment with the screw and blocks. This construction affords great rapidity in the assembling of the device.

15 As seen from the drawing, the two lugs 19 are preferably provided for each armor section. One of the lugs is formed at the lowest point of a curve 22 on the upper portion of each section, while the other or lower lug is 20 made simultaneously with the punching of a hexagon opening 23 in the armor sections and is adapted to register with one of the corresponding recesses 20 in said blocks. The lugs are so positioned with respect to the screws 25 as to extend in back to back relation, as shown in the drawing. This insures that the armor will be effectively anchored at the recesses. If considerable tension is used on the screws, the lugs, being free-ended, are adapt- 30 ed to act as a spring and will be deflected partially toward each other, making a good bearing contact with the insulating blocks within the recesses 20. The lower edge portions of the armor sections preferably terminate flush 35 with the surface of the leading end of the plug body so as to keep said end free from metal and thus eliminate possible accidental short circuit.

It will thus be seen that there is provided a 40 device in which the several objects of this invention are achieved, and which is well adapted to meet the conditions of practical use.

As various possible embodiments might be 45 made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A connector of the character described 55 including a body portion of insulating material having a recess, an armor to protect said portion, said armor having a resilient lug extending into the recess, and means co-operating with said lug for fastening said armor on said portion, said lug extending only partially around and beneath said means.

2. A plug connector comprising a body 60 portion of insulating material, an armor to protect said portion, said armor having a

resilient projection extending therefrom, and means co-operating with said projection for fastening said armor on said portion.

3. A plug connector comprising a body 70 portion of insulating material having a recess, an armor to protect said portion, said armor having a resilient member extending into the recess and means co-operating with said member for fastening said armor on said portion.

4. An armor adapted to be fitted over the insulated body portion of a plug connector, 80 said armor comprising two separable sections of identical construction, each section having a pair of spring tongues, said tongues constituting alignment means for snugly fitting the armor sections to said body portion, and fastening means engaging said tongues for retaining the parts forming said body portion assembled.

5. In combination with a plug connector having a two-piece insulating body portion secured together with fastening means, an armor for protecting said body portion comprising two identical sections formed of sheet material housing said body portion, each section having an inwardly extending bent resilient lug formed integrally with said section and engaging with said fastening means.

In testimony whereof I affix my signature.

HARRY HERTZBERG.
